UNITED STATES PATENT OFFICE.

FELIX J. ROGERS, OF CRAFTON, PENNSYLVANIA.

TROLLEY.

SPECIFICATION forming part of Letters Patent No. 655,014, dated July 31, 1900.

Application filed January 3, 1900. Serial No. 202. (No model.)

To all whom it may concern:

Be it known that I, FELIX J. ROGERS, a citizen of the United States of America, residing at Crafton, in the county of Allegheny 5 and State of Pennsylvania, have invented certain new and useful Improvements in Trolleys, of which the following is a specification, reference being had therein to the accompanying drawings.

My invention relates to certain new and useful improvements in trolleys, and is particularly adapted to be employed in connection with overhead-trolley systems, and has for its object to attain a constant connection 15 between the motor of the car and the overhead or current wire.

In overhead-trolley systems considerable trouble has been experienced in retaining the trolley-wheel in engagement with the overhead or current wire and the consequent breaking or discontinuance of the motive current. I aim to overcome this objection by the provision of an auxiliary trolley-pole upon which a trolley-wheel is mounted, together 25 with novel means of construction which will permit of the movement of said auxiliary trolley-pole, so as to permit the same to retain the trolley-wheel in engagement with the trolley-wire.

Briefly described, the invention comprises, in combination with a trolley-stand, which is mounted upon a car, a trolley-pole mounted to swing upon said stand with a spring connected to the stand and engaging said pole 35 for holding the same normally elevated, and an auxiliary trolley-pole mounted upon the trolley-pole proper with a tension-spring so arranged as to hold the wheel of the auxiliary trolley-pole in engagement with the wire, with 40 means connected to the auxiliary trolley-pole for limiting the movement imparted thereto by its spring.

The novel features of construction will be hereinafter specifically described and then 45 particularly pointed out in the appended claims, and in describing the invention in detail reference is had to the accompanying drawings, forming a part of this specification, wherein like numerals of reference indicate 50 corresponding parts throughout the several views, in which—

Figure 1 is a side view of my improved trol-

ley with the pole partly broken away and the stand partially in section. Fig. 2 is a front view of the same. Fig. 3 is a sectional view 55 of the sleeve which is mounted upon the trolley-pole proper for attaching the auxiliary pole thereto. Fig. 4 is a plan view of one of the keepers attached to the trolley-pole proper and to the auxiliary pole for limiting the movement of the latter.

Referring to the drawings by reference-numerals, 1 indicates a suitable casting which is mounted upon the top of the car and is provided with a peripheral flange 2, which 65 forms a bearing for the revoluble plate 3, upon which the trolley-pole proper is mounted. This plate 3 is held in position upon the trolley-stand by means of an annulus 4, which is bolted or otherwise secured to the flange 70 of the stand and is provided on its inner edge with a groove 5, which is adapted to receive the periphery of the plate 3. This plate 3 is provided on its upper face with a standard or lug 6, upon which the trolley-pole 7 is 75 mounted by securing the lower end of said trolley-pole in a ferrule 8, having a bifurcated or yoked end 9 to engage the sides of the lug or standard 6 and secured thereto by a journal-bolt 10, which projects outwardly for 80 some distance at each side of the trolley-pole and has arranged in each of its projecting ends a pair of headed pins 11. The standard or lug 6 is arranged upon the upper face of the plate 3 toward one edge thereof, and adjacent to the opposite edge of the plate is arranged a pair of eyes 12, which are adapted 85 to receive the ends of a substantially U-shaped tension-spring 14, the cross-bar 15 of which connecting the two members of the 90 spring engages the underneath face of the trolley-pole proper and retains the pole normally in an elevated position, the said members of the spring 14 passing over the projecting ends of the journal-bolt 10 between 95 the pairs of headed pins 11, and the latter serving to retain the spring in position. The ends of the spring are preferably screw-threaded, and the tension may be increased or diminished by adjusting the nuts 16, which 100 are mounted on said screw-threaded ends.

The trolley-pole 7 has mounted thereon at a suitable point a sleeve 17, which may be readily fastened to the trolley-pole 7 by a

key 18, pressed firmly against the trolley-pole by means of set-screw 19, operating through the under side of said sleeve. On its upper face this sleeve carries a standard or lug 20, 5 to which is pivotally attached an auxiliary trolley-pole 21. This auxiliary trolley-pole has a trolley-wheel 22 mounted on its upper end, with a moving cord or cable 23 connected thereto at any suitable point. The trolley- 10 wheel is held in constant engagement with the current-wire by means of a substantially U-shaped spring 24, the two members of which engage through the eyes 25, provided therefor on the sleeve 17, and have their free 15 ends screw-threaded and held by nuts 26 in the same manner as a spring 14 is held on the trolley-stand. The cross-bar connecting the two members of this spring 24 engages underneath the auxiliary trolley-pole 21, so 20 as to hold the wheel carried by the latter in contact with the current-wire. The forward movement which might be imparted to the auxiliary trolley-pole by the spring 24 in case the trolley-pole was in engagement with the 25 current-wire is limited by a yoke or clevis 27, the arms of which pass through the keeper 28, which is shrunk or otherwise secured to the auxiliary trolley-pole a short distance above its pivotal connection with the trolley- 30 pole 7 and through a like keeper 29, which may be secured in any desirable manner upon the trolley-pole 7 above the point of connection of the auxiliary trolley-pole with trolley-pole 7, said arms being screw-threaded at 35 their free ends and having mounted thereon nuts 30, which are of a greater size than the eyes of the keepers 29, in order that when they engage said keeper the movement of the pole 21 will be arrested.

40 When it is desired to remove the trolley-wheel from engagement with the current-wire, the pull upon the cable or cord 23 will draw the pole 21 downward, compressing the spring 24 and allow such removal, while during the 45 travel of the car the spring 24, assisted by the action of the spring 14 against the trolley-pole 7, will serve to hold the trolley-wheel in engagement with the wire at all times, and during the passing of the car over switches 50 or the like the rotary movement of the plate 3 will allow of the trolley-wheel alining and remaining in engagement with the current-wire.

Having thus fully described my invention, 55 what I claim as new, and desire to secure by Letters Patent, is—

1. In a trolley for electric cars, the combination, of a plate rotatably mounted in a trolley-stand and provided with eyes, a trolley- 60 pole pivotally secured to said plate, a substantially U-shaped spring mounted upon

the pivotal pin of the trolley-pole with the cross-bar which connects its two members engaging the underneath face of the trolley-pole and its ends adjustably secured in the 65 eyes on the plate, a sleeve mounted upon said pole and provided with eyes, an auxiliary trolley-pole pivotally secured to said sleeve with a trolley-wheel mounted on its upper end, a substantially U-shaped spring 24 having its 70 ends adjustably mounted in said eyes and the cross-bar connecting the two members engaging the underneath face of the auxiliary trolley-pole, a keeper 28 mounted on the auxiliary trolley-pole, a like keeper 29 mounted 75 on the trolley-pole proper, and a yoke or clevis engaging said keepers for limiting the upward movement of the auxiliary trolley-pole, as and for the purpose described.

2. In a trolley for electric cars, the combination, with the plate 3 rotatably mounted in a trolley-stand, of a trolley-pole pivotally mounted on said plate with its pivot-pin extending outward on each side of the pole, a substantially U-shaped spring mounted on 80 the pivot-pin of the trolley-pole with its ends adjustably connected to the plate and its cross-bar engaging the trolley-pole, a sleeve mounted upon said trolley-pole, an auxiliary trolley-pole pivotally mounted on said sleeve, 85 a substantially U-shaped spring 24 having its ends adjustably connected to said sleeve with its cross-bar engaging the auxiliary trolley-pole, a trolley-wheel journaled in the free end of said auxiliary trolley-pole, and 90 means carried by the auxiliary trolley-pole and engaging the trolley-pole proper to limit the upward movement of said auxiliary pole, as and for the purpose set forth.

3. In a trolley for electric cars, the combination, with the rotatably-mounted plate, of the trolley-pole 7 pivotally mounted on said plate, a tension-spring engaging said pole with its ends adjustably connected to the plate, an auxiliary trolley-pole pivotally 100 mounted on the trolley-pole 7, a tension-spring 24 engaging said auxiliary trolley-pole with its ends adjustably connected to the trolley-pole 7, a trolley-wheel journaled in the outer end of said auxiliary trolley-pole, 105 keepers 28, 29 mounted on the auxiliary trolley-pole and trolley-pole respectively, and a yoke or clevis operating in said keepers to limit the upward movement of the auxiliary trolley-pole, substantially as shown and de- 110 scribed.

In testimony whereof I affix my signature in the presence of two witnesses.

FELIX J. ROGERS.
